WINDOW OPERATOR

Anton Rappl, Buffalo, N. Y., assignor to Trico Products Corporation, Buffalo, N. Y.

Application May 4, 1942, Serial No. 441,611

4 Claims.

(Cl. 192—67)

This invention relates to certain new and useful improvements in window operators for motor vehicles and more particularly to the fluid type of operator, although the use of the invention is not confined to such type.

It has heretofore been proposed to open and close the windows of automobiles by means of fluid motors connected to the intake manifold of the vehicle engine, locking means having been employed to prevent the surreptitious opening of the windows from without, together with emergency release means effective at least to partially open a window to enable the latter being manually grasped for completing its opening movement in the event the source of operating pressure had failed. The construction and arrangement, while practical, were not of sufficient flexibility to conveniently adapt itself to the various styles and designs of vehicle bodies and door structures.

The object of the present invention is to provide a construction wherein is provided a greatly increased flexibility of mounting and adaptation by which the emergency release is rendered more accessible and the entire arrangement more practical for general application. Further, the invention comprehends an emergency release utilizing a simple remote control by which the release is more readily placed under the control of the motorist or passenger.

In the drawings,

Fig. 1 is a diagrammatic illustration of a vehicle window and an operator therefor embodying the present invention;

Fig. 2 is a horizontal sectional view through the release control with parts left in elevation;

Fig. 3 is an inside elevation of the release control, with a portion broken away;

Figs. 4 and 5 are detailed sectional views about on lines 4—4 and 5—5, respectively, of Fig. 3; and

Fig. 6 is a fragmentary sectional view, partly in elevation, through the fluid motor.

Referring more particularly to the drawings, the numeral 1 designates a vehicle window slidably in vertical guideways 2 by means of a slidably connected work arm 3 of a modified bell crank lever, the latter being rockably mounted by a shaft 4 journaled in a mounting bracket 5. The work arm is fixed to the shaft by being fitted upon a portion 6 thereof having a non-circular cross section, and the weight of the window panel is counterbalanced by a flat coiled spring 7 having its inner end engaged in a slot 8 on the shaft and its outer end anchored on a lug 9 struck out

from the mounting bracket. It is therefore clear that as the window is lowered it will rock the work arm 3 to wind the counterbalance spring.

The power arm 10 of the bell crank lever is pivoted on the round portion 11 of the shaft and is mechanically interlocked with the work arm by means of a lock bolt 12 engaging in a recess 13 in the work arm 3. The lock bolt 12 is carried by a plate 14 abutting the power arm and connected thereto by a spring plate 15 for hinging or springing action to enable the bolt's being retracted from the bolt hole 13 in the work arm 3 to disconnect the two arms for a purpose hereinafter disclosed. The plate 14 really constitutes a part of the power arm and overlies the recessed part of the work arm.

The fluid motor comprises a piston 16 operable in the motor chamber 17 and pivotally connected by its rod 18 to the power arm 10 so that when the motor operates under pressure differential the bell crank lever unit will rock and move the window accordingly. The pressure differential is provided by the selective operation of the control valves 19 and 20 inserted in branch conduits 21 and 22 from the pressure supply line 23 which latter may lead to the intake manifold or other source of operating pressure. The piston may be self-locking and for this reason comprises a rod fixed section 24 and a relatively movable or floating section 25 each section having fluid sealed contact with the chamber wall to be responsive to a definite pressure differential. An expansible shoe 26 is interposed between the piston sections and movably connected to the floating section for radial movement. A cam surface 27 on the shoe opposes a cam face 28 on the piston rod or fixed piston section to cooperate therewith through an interposed roller 29 in expanding the shoe against the chamber wall and thereby lock the window when an attempt is made to open the window. However, should the occasion arise to open the window manually when the motor is dead through failure of the pressure supply, then the bolt 12 is disengaged from the work arm to permit a spring 30, normally held compressed between the two arms, to act through the work arm in pulling the window down sufficiently to enable its being grasped by the hand for further opening. The foregoing construction and operation are similar to the disclosure in my earlier application for patent on a window operator, filed November 5, 1940, under Serial No. 364,421.

The present invention deals primarily with the release of the window from the motor. The bolt carrying plate 14 is formed with a free marginal

ledge 31 of arcuate shape disposed concentric with the axis of rocking of the bell crank lever. This ledge is engaged by an actuator, such as a terminal crank arm 32 of a rock shaft 33 which is journaled in a nearby swivel bearing support 34 pivotally supported on the mounting bracket 5. The swivel support is formed with an open bearing and the shaft is held therein by the overlying ledge 31. This bearing support for the shaft is located close to the crank arm so that the outer end of the shaft may be given a greater angular adjustment without operatively dislocating the crank arm from the ledge. Such permissive adjustment of the crank part gives a wider field from which to select the proper location for the actuating button 35 at the opposite end of the rock shaft. The button is supported by a spring 36 within a housing 37 removably secured to a mounting base 38, the latter being mountable in a selected position on the door or vehicle body by attaching screws 39 and carrying a bearing support 40 for the outer end of the shaft. Such outer end terminates in a crank arm 41 which engages in an eye in the stem 42 of the button so that depression of the button will rock the shaft and lift the spring plate 14 to retract the lock bolt 12 and release the window or closure connected arm from the fluid motor. A retaining plate 43 holds the shaft in the bearing 40 against accidental displacement.

By this simple construction the installation is greatly facilitated in that a most desirable location for the release button 35 may readily be found within the wide range of angular adjustment or displacement of the rock shaft and thereafter the button secured to the door body. Thus the release control is disposed in a position easily accessible to the passenger.

While the foregoing description has been given in detail for clarity it is obvious that the inventive principles therein contained are susceptible of other physical embodiments without departing from the spirit of the invention and therefore it is not intended thereby to restrict the invention as defined in the appended claims.

What is claimed is:

1. A closure operator comprising relatively movable drive and driven parts operable in a definite path back and forth, means detachably connecting said parts for movement as a unit and enabling the driven part to be disconnected from the driving part, a mount supporting the unit for such back and forth movement, a swivel bearing journaled on the mount alongside the path for turning about an axis lying transverse the plane of movement of said parts, and a rock shaft journaled in the swivel bearing and adjustable therewith about such axis and in a plane sub-

stantially parallel to the first plane, said shaft being operatively connected to said connecting means by a play connection for disconnecting the driven part from the driving part from any

5 predetermined adjustment of the shaft about the swivel bearing axis, whereby to facilitate the location of the rock shaft in an accessible position.

2. A closure operator comprising relatively 10 movable drive and driven parts operable in a definite path back and forth, means detachably connecting said parts for movement as a unit and enabling the driven part to be disconnected from the driving part, a mount supporting the unit 15 for such back and forth movement, a swivel bearing journaled on the mount alongside the path for turning about an axis lying transverse the plane of movement of said parts, and a rock shaft journaled at one end in the swivel bearing and 20 angularly adjustable therewith as a unit about such axis for accessible placement of the opposite end of the shaft, the first end of the shaft having a crank part and said connecting means having a bearing face overhanging the crank part 25 and beneath which face the crank part remains during such unit angular adjustment of the shaft and swivel bearing for actuating said connecting means from any position within the limits of angular adjustment.

3. A closure operator comprising relatively 30 movable parts, means detachably connecting said parts for movement as a unit, a member mounting the unit, an open swivel bearing on the member, a rock shaft having one end portion journaled in the bearing and formed with an adjacent crank part, said connecting means including a movably mounted part overlying the crank part to be actuated thereby and serving to hold the rock shaft in the bearing, and means on the 40 opposite end portion of said shaft for rocking the same, said rock shaft and said swivel bearing being angularly adjustable as a unit about the axis of the swivel bearing to facilitate placement of said rocking means in an accessible position.

4. A closure operator comprising relatively 45 movable parts, means detachably connecting said parts for movement as a unit, a member mounting the unit, said connecting means embodying a plate abutting one of said parts and lying upon the companion part, a spring plate anchored to said one part and to said abutting plate to constitute a spring hinge mounting for the latter, a locking lug carried by the abutting plate and engageable in a recess in said companion part to 50 lock the two parts together, and means for moving the abutting plate to disengage the lug.
